GRAIN DRYING APPARATUS

Charles William Zollman, Walton, Ind.

Application February 10, 1955, Serial No. 487,332

4 Claims. (Cl. 34—224)

This invention relates to drying apparatus, and more specifically, to a device for drying grain and other related substances.

One of the primary objects of this invention is to provide a device of the type described for drawing moisture from the interior of grain without permitting the formation of a hard exterior coating thereon, the formation of such a coating comprising a deleterious characteristic commonplace in grain dried by conventional means.

Another object of this invention is to provide a grain drying bin with means for effecting the drying thereof at a uniform rate.

A still further object of this invention is to provide a grain drying apparatus which is inexpensive to manufacture and maintain, non-complex in construction and assembly, and durable in use.

Other and further objects and advantages of the present invention will become more evident from a consideration of the following specification when read in conjunction with the annexed drawings in which:

Figure 1 is a top plan view of grain drying apparatus constructed in accordance with the present invention.

Figure 2 is a longitudinal cross-sectional view taken on the horizontal plane of line 2—2 of Figure 1, looking in the direction of the arrows.

Figure 3 is a cross-sectional view taken on the horizontal plane of line 3—3 of Figure 2, looking in the direction of the arrows.

Figure 4 is an enlarged detail elevational view, partly in section, taken on the vertical plane of line 4—4 of Figure 2, looking in the direction of the arrows.

Figure 5 is a detail cross-sectional view taken on the line 5—5 of Figure 2, looking in the direction of the arrows.

Referring now more specifically to the drawings, reference numeral 10 designates, in general, grain drying apparatus constructed in accordance with the teachings of the instant invention. As illustrated therein, the grain drying apparatus is seen to comprise an elongated substantially hollow cylindrical member 12 having a closure wall 14 extending across the lower end thereof and integrally formed therewith.

The closure wall 14 is centrally apertured at 16 and receives therethrough one end of an elongated substantially hollow tubular conduit 18 having flanges 20, 22 disposed, respectively, adjacent the opposed ends thereof. As is clearly seen in Figure 2, the flange 20 bears against the closure wall 14 and prevents displacement of the conduit in a downward direction.

The other end of the conduit 18 extends through a centrally positioned aperture 24 formed in the closure wall 26 disposed at one end of an elongated substantially hollow cylindrical member 28 formed of wire mesh. The closure wall 26 is seated on the flange 22 and is maintained thereby in spaced relation relative to the closure member 14.

A plurality of substantially triangularly shaped perforated spacers 30 extend between the cylindrical mem-

2

ber 12 and are fixedly secured to the cylindrical member 28, the spacers 30 being disposed in circumferential spaced relationship and serve to maintain the cylindrical member 28 in coaxial alignment with the cylindrical member 12.

To the other end of the conduit 18 is fixedly secured by conventional means one end of a second elongated substantially hollow cylindrical member 36 formed of wire mesh. The other end of the second wire mesh cylindrical member terminates in confronting relationship relative to one end of an elongated substantially hollow tubular conduit 38. A collar 40 surrounds and is secured to the aforementioned adjacent ends of the cylindrical member 36 and conduit 38. The other end of the conduit 38 is seated and secured in a central opening 42 formed in a substantially circular removable cover member 44 having a laterally extending circumferential flange 46. As seen in Figure 2 of the drawings, the cover member 44 extends entirely across the cylindrical member 12.

An opening is formed in the cylindrical member 12 adjacent the closure wall 14 to which is connected one end of a conduit 48. The other end of the conduit 48 is connected, by conventional means, with the lower end of a substantially hollow rectangular plenum chamber 50. The plenum chamber 50 includes a bottom wall 52, a pair of oppositely disposed end walls 54, 56, a pair of oppositely disposed side walls 58, 60, and a removable closure member 62.

A conventional blower and heating unit therefor is disposed within the plenum chamber 50 and is designated, in general, by the reference numeral 64. Any convenient and conventional means well known in the art may be utilized for supporting the blower 64.

As is seen in Figures 2 and 5 of the drawings, the blower 64 is seen to comprise a casing 66 in which is mounted a hub 68 having a plurality of radially spaced collar blades 70 fixedly secured thereto. A plurality of arms 72 have one of their ends fixedly secured to the hub 68 and the other ends thereof are rigidly connected to a collar 74 mounted for rotation with the drive shaft 76 of an electric motor 78. The motor 78 is formed with a flange 80, the latter being secured to the side wall 58 of the plenum chamber 50 as by bolts 82. The inner end of the shaft 76 extends through an opening 84 formed in the side wall 58, and the other end thereof extends through an aperture 86 formed in the side wall 60 and terminates in a journal or bearing 88 fixedly secured to the side wall 60. A thrust collar 90 is secured on the outer end of the shaft 76.

A plurality of electric heating elements 92 are disposed within a casing 93 which includes a pair of concentrically disposed and coaxially arranged side walls 94, 96 having closed ends 98 and 100. The casing 93 is secured to the side wall 60 by bolts 102 and is positioned within the hub 68 in coaxial relationship relative to the shaft 76.

The blower is provided with an intake pipe 104 which extends through the end wall 56 for communication with the ambient atmosphere, the intake pipe 104 being provided with a valve 106 mounted on a shaft 108 which projects through the side wall 60, the outer end of the shaft 108 having fixedly secured thereto an operating handle 110. The blower 64 discharges through pipe 112 into the conduit 48.

The bottom wall 52 of the plenum chamber 50 has an opening formed therein adjacent the end wall 56, the opening receiving therethrough one end of an elongated tubular conduit 114, the other end of which is fixedly secured within the first-mentioned end of the pipe 18. A butterfly valve 116 is mounted on a shaft 118 having an end thereof projecting through the side wall 60. A manually operated handle 120 is fixedly secured on the projecting end of the shaft 118.

In operation, the cover member 44 is removed from the upper ends of the cylindrical members 12 and 28. The grain to be dried is then poured into the wire mesh cylindrical member 28 and the cover replaced. The valve 106 is turned to its closed position as shown in Figure 2 and the valve 116 is turned to its open position. The motor 78 is then energized to effect rotation of the impeller blades 70. As the blower 64 is operated, air is discharged through the pipe 112 which then passes into the conduit 48 and thence into the cylindrical member 12 below the closure wall 26. The air then circulates upwardly between the cylindrical members 12 and 28 and, being under pressure, will pass through the grain. As this circulation of air takes place, moisture is removed from the interior of the grain kernels and this moisture becomes entrained with the air and discharges from the grain through the wire mesh member 36.

At this point, some of the moisture laden air is discharged through the conduit 38 into the atmosphere while a greater portion thereof will pass downwardly through the conduit 18 and the pipe 114 to the plenum chamber 50. The continuous actuation of the blower 64 brings about a recycling of the moistened air.

The continued recycling of the moisture bearing air through the grain prevents a hard coating from forming on the grain, the latter being objectionable to grain purchasers.

After the moisture within the grain kernels has been substantially reduced from the interior thereof, the electrical heating elements 92 are energized in order to circulate hot air, substantially devoid of moisture, through the grain. At this time the valve 106 is turned to its open position and the valve 116 is moved to its closed position. When the desired degree of dryness has been obtained, the motor 78 and the heating elements 92 are deenergized. The removable cover 44 is then taken from the upper ends of the cylindrical members 12 and 28, and the grain within the wire mesh cylindrical member 28 is then removed.

Having described and illustrated one embodiment of this invention, it will be understood that the same is offered merely by way of example, and that the invention is to be limited only by the scope of the appended claims.

What is claimed is:

1. A grain drier comprising an elongated substantially hollow cylindrical member having a closure wall at one end thereof, a grain receiving elongated substantially hollow cylindrical wire mesh member having a closure member at one end thereof, said wire mesh member being disposed within said first cylindrical member in concentric relationship and with said closure members disposed in spaced confronting juxtaposition, a removable closure member extending across and supported on the other ends of said cylindrical members, said closure members each having a centrally positioned aperture extending therethrough and aligned with each other, an elongated pipe having a radial flange adjacent each end thereof, said pipe having an end thereof extending through

said aperture formed in the closure member of said first cylindrical member with said flange adjacent the marginal edge of said aperture, the other end of said pipe engaging through said aperture formed in said closure member of said grain receiving cylindrical member with said flange adjacent thereto engaging the marginal edge of said last-named aperture, an elongated cylindrical member formed of wire mesh disposed within said grain receiving cylindrical member and having an end thereof secured to said other end of said pipe, the other end of said cylindrical member being fixedly secured to one end of a conduit having its other end secured within said aperture formed in said removable closure member, and means connected with said first cylindrical member for circulating air within said first, second and third cylindrical members.

2. A grain drier as defined in claim 1, and last-named means comprising a blower.

3. A grain drier as defined in claim 1, said last-named means comprising a blower, and means for heating the air discharged from said blower.

4. A grain drying bin comprising an elongated substantially hollow cylindrical member having a closure member at one end thereof, a second elongated substantially hollow cylindrical member formed of wire mesh disposed within said first cylindrical member, a closure member for one end of said second cylindrical member, a third elongated substantially cylindrical member formed of wire mesh and disposed within said second cylindrical member, means securing said cylindrical members in coaxial spaced relationship, means supporting said closure member of said second cylindrical member in spaced confronting relationship relative to said closure member for said first cylindrical member, an air impelling device, means connecting the discharge side of said air impelling device with said first cylindrical member adjacent its said closure member, means for heating the air discharged from said air impelling device, a removable cover extending across the other ends of said first and second cylindrical members, said removable cover having a centrally positioned opening formed therein, a conduit having one of its ends fixedly secured within said opening, said conduit having the other of its ends connected with one end of said third cylindrical member, the other end of said third cylindrical member being connected with one end of a substantially hollow tubular conduit, and means connecting the other end of said last-named tubular conduit with the intake port of said blower.
